UNITED STATES PATENT OFFICE.

EUGENE GARRETSON AND EDWARD W. SCHLENKER, OF BUFFALO, NEW YORK.

THERMO-ELECTRIC GENERATOR.

1,162,049.

Specification of Letters Patent.

Patented Nov. 30, 1915.

Application filed March 12, 1914. Serial No. 824,183.

To all whom it may concern:

Be it known that we, EUGENE GARRETSON and EDWARD W. SCHLENKER, citizens of the United States, residing at Buffalo, in the county of Erie and State of New York; have invented new and useful Improvements in Thermo-Electric Generators, of which the following is a specification.

This invention relates to a thermo-electric generator which is more particularly designed for use in therapeutic instruments in which the thermo-electric effect is produced by cooling the instrument either by immersing the same in cold water or otherwise chilling the same.

It is the object of this invention to provide a simple and efficient device of this character which is compact in construction, which is quick in action and has a comparatively large output for the size of the instrument.

In the accompanying drawings: Figure 1 is a longitudinal sectional elevation of a therapeutic instrument embodying our invention. Fig. 2 is a transverse section thereof taken in the correspondingly numbered lines in Fig. 1.

Similar characters of reference indicate corresponding parts in both views.

In its general organization our invention comprises a plurality of thermo-pile couples of peculiar construction which are so disposed that when the instrument containing the same is chilled some parts of the thermo-pile couples are also immediately chilled while other parts thereof are not immediately chilled, thereby producing a thermo-electric current due to this differential chilling until such time as all parts of the thermo-pile couples have become uniformly chilled. The current so produced may be utilized for determining the temperature of the water or other chilling agent with which the instrument is associated preparatory to using the same for therapeutic purposes and also for ascertaining the completeness of the thermo-electric circuits in the instrument and its accessories.

The thermo-electric detecting devices

forming part of our invention are inclosed in the same casing or shell which contains the diamagnetic bodies wherein diamagnetism is intensified for therapeutic purposes. This casing may be variously constructed but as shown in the drawings the same comprises a central body section 1 of sheet metal and two end caps or heads 2, 3 of metal applied to opposite ends of the body.

The thermo-pile embodying our invention is arranged in the central part of the casing and is constructed as follows:—4, 5 represent two partitions or transverse walls mounted in the front and rear parts of the cylindrical body of the casing and preferably constructed of iron. Arranged axially within the casing and connected at its front and rear ends with the front and rear partitions is a tie rod 6 which is also preferably constructed of iron. Upon this tie rod is arranged a tube or sleeve 7 of insulating material such as rubber. 8 represents a plurality of disks, preferably of iron, forming one of the two kinds of thermo-electric elements and mounted side by side on the insulating sleeve and each provided at its margin with a rearwardly projecting annular flange. The several disks are insulated from each other by insulating disks 9 of rubber, fiber or similar material extending from the insulating sleeve to the bore of the casing and each engaging on one side with the unflanged side of one of the elements 8 while its opposite side engages the flange of the adjacent element 8. The foremost element 8 is also insulated by a disk 10 of rubber or the like from the front partition 4. Each of the disk elements is provided on diametrically opposite sides with curved openings 11, forming a hub 12 of comparatively large area at the center of the disk element, a rim 13 of comparatively large area, and two radial arms 14 of comparatively small area connecting diametrically opposite sides of said hub with the rim, as shown in Fig. 2. In its hub each of the disk elements is provided with a notch 15 projecting from its bore outwardly.

represents a plurality of strip-shaped thermo-electric elements, preferably constructed of nickel, and each arranged radially on the front side of one of the insulating disks and electrically connected at its outer end with the flange of the disk element in front of the same while its inner end is provided with a lip 16 which projects rearwardly through the notch 14 in 10 the next rearward disk element and is bent outwardly and electrically connected with the rear side of the last mentioned disk element. By this means a plurality of thermo-electric couples or pairs are formed which 15 are electrically joined in series.

Various means may be employed for conducting the current generated by this thermo-pile to the exterior of the casing or shell, those shown in the drawings being suitable 20 and constructed as follows:—The foremost disk element is provided with a terminal 17 which projects forwardly through an opening in the front partition and is connected electrically with the inner end of a 25 conducting wire 18 which forms one of a pair and is secured in a plug 19 mounted in the front head of the casing. The metal casing forms the other terminal of the thermo-pile by reason of the rearmost disk element 30 engaging with the rear partition and the engagement of both partitions with the casing and the tie rod connecting the partitions. The casing is electrically connected with the other conducting wire 20 secured in 35 the plug 19. 21 represents a galvanometer which may be of any suitable construction and which has its terminals connected with opposite sides of said thermo-pile, by means of the two wires 18, 20. Upon placing this 40 shell or casing into cold water or in contact with some other chilling agent the outer portions of the couples of the thermo-pile close to the inner side of the shell or casing will also be chilled or cooled by radiation 45 while the inner parts of these couples which are remote from the influence of temperature changes will not be effected immediately. A thermo-electric current due to this difference in the temperature of different parts of 50 the couples is therefore produced which current is conducted through the electric circuit which includes the electric indicating or recording device and thus permits of determining the temperature to which the device 55 has been chilled. Generation of this current continues and its strength is readable on an indicating device until the innermost parts of the thermo-pile couples have also been chilled and are of the same temperature 60 as the outer parts. The duration of the current is, however, ample to permit of accurate measurement and observation. By this means the temperature of the cooling agent

may be accurately determined so as to enable the diamagnetic therapeutic devices 65 which are arranged in another part of the inclosing shell or casing and which is dependent for its operation upon submergence into sufficiently cool water or in contact with a like cooling agent of another character to be used most effectively. By making the arms 14 of the disk elements of less area than the rims and hubs thereof the transmission of the cooling effect from the rims to the hubs is retarded, thereby prolonging 75 the electrical output of thermo-pile accordingly and permitting the same to be used for a longer time before all parts of the elements are of equal temperature and the generation of current is arrested.

The lines or wires which connect the thermo-pile with the indicating device also serve as conductors of the current from the interior of the casing to the patient for therapeutic purposes, and the thermo-pile 85 and indicating device therefore also serve as a means for testing the continuity of the internal as well as the external connections of the circuit through which the therapeutic current is subsequently conducted.

We claim as our invention:

1. A device of the character described comprising a metal casing, a plurality of disk elements arranged side by side in said casing and each provided at its periphery with an annular flange, a plurality of strip elements each of which has its outer part connected with the outer part of one disk element and its inner part connected with the inner part of another disk element, and a plurality of insulating disks each arranged between the flanged side of one disk element and the unflanged side of another disk element.

2. A device of the character described comprising a metal casing, a plurality of disk elements arranged side by side in said casing and each having a large area rim, a large area hub and a small area arm connecting the rim and hub, and a plurality of strip elements each connected at its outer end with the outer part of one disk element and at its inner end with the inner part of another one of said disk elements.

3. A device of the character described comprising a metal casing, two metal partitions engaging with the front and rear parts of said casing, a tie rod connecting said partitions, a plurality of pairs of thermo-electric elements arranged within the casing between said partitions, the foremost element having a terminal projecting through the front partition and the rearmost element engaging with the rear partition.

4. A device of the character described comprising a metal casing, two metal parti-

tions engaging with the front and rear parts of said casing, a tie rod connecting said partitions, an insulating sleeve arranged on said tie rod, a plurality of pairs of thermo-electric elements arranged between said partitions and around said sleeve, and insulating disks arranged between adjacent couples of thermo-electric elements.

Witness our hands this tenth day of March, 1914.
